UNITED STATES PATENT OFFICE.

JEAN PIRARD, OF CHICAGO, ILLINOIS.

DETERGENT.

SPECIFICATION forming part of Letters Patent No. 645,373, dated March 13, 1900.

Application filed September 29, 1899. Serial No. 732,025. (No specimens.)

To all whom it may concern:

Be it known that I, JEAN PIRARD, a citizen of the United States, residing at Chicago, in the county of Cook and State of Illinois, have ⁵ invented a new and useful Compound for Dry Cleaning, of which the following is a specification.

This invention relates to cleaning compounds in general, and more particularly to ¹⁰ that class employed in the process known as "dry cleaning;" and it has for its object to provide a compound which will be effective in removing grease and other dirt from fabrics and in which, moreover, the delicate ¹⁵ colors and structures will not be destroyed or injured in any way, the invention combining with certain cleaning agents which are normally injurious certain other ingredients which, while not affecting the cleaning properties, prevent the injurious action of these ²⁰ desirable substances.

The compound consists of two hundred and eighty parts of benzin; water, forty-two parts; soap, twenty-one parts; gum-arabic, fifteen ²⁵ parts; glycerin, thirty-six parts; ammonia, thirty parts; chloroform, twenty-five parts; sulfuric ether, thirty parts; sodium chlorid, thirty parts, and linseed-oil forty parts.

In preparing the compound the sodium ³⁰ chlorid is dissolved in the water at 212°. The mixture is then allowed to cool, after which the gum-arabic, glycerin, ammonia, chloroform, and sulfuric ether are added, and the compound is allowed to stand for six hours.

³⁵ The linseed-oil and soap are then mixed into

the compound, and it is allowed to stand one hour, after which the benzin is added, and the material is ready for use.

I am aware that benzin, chloroform, sulfuric ether, and ammonia have been used for ⁴⁰ cleaning both alone and in combination with themselves and other ingredients; but the resultant compounds are too strong for delicate colors and fabrics, while the glycerin, gum-arabic, and linseed-oil tone down these nor- ⁴⁵ mally-injurious ingredients and while preserving their cleaning properties prevent them injuring the material cleaned.

What is claimed is—

1. The herein - described cleaning com- ⁵⁰ pound, consisting of the ingredients and the proportions as follows: benzin, two hundred and eighty parts; water, forty - two parts; soap, twenty-one parts; gum-arabic, fifteen parts; glycerin, thirty-six parts; ammonia, thirty parts; chloroform, twenty-five parts; sulfuric ether, thirty parts; sodium chlorid, thirty parts; linseed-oil, forty parts.

2. A cleaning compound consisting of benzin, water, soap, gum-arabic, glycerin, am- ⁶⁰ monia, chloroform, sulfuric ether, sodium chlorid, and linseed-oil.

In testimony that I claim the foregoing as my own I have hereto affixed my signature in the presence of two witnesses.

JEAN PIRARD.

Witnesses:

ELIE VEZINA,
P. J. CORBEIL.
